US00D903530S

(12) **United States Design Patent** (10) Patent No.: **US D903,530 S**
Choi et al. (45) Date of Patent: ** Dec. 1, 2020

(54) **RACING KART**

(71) Applicant: **MONOLITH INC.**, Jeju-si (KR)

(72) Inventors: **Ji Woong Choi**, Seoul (KR); **Gyu Hyuk Jung**, Jeju-si (KR); **Na Young Kim**, Jeju-si (KR)

(73) Assignee: **MONOLITH INC.**, Jeju-si (KR)

(**) Term: **15 Years**

(21) Appl. No.: **35/507,515**

(22) Filed: **Apr. 15, 2019**

(80) **Hague Agreement Data**

Int. Filing Date: **Apr. 15, 2019**

Int. Reg. No.: **DM/202381**

Int. Reg. Date: **Apr. 15, 2019**

Int. Reg. Pub. Date: **Oct. 18, 2019**

(51) **LOC (12) Cl.** 12-08

(52) **U.S. Cl.**

USPC **D12/87**

(58) **Field of Classification Search**

USPC D12/87

CPC F16H 57/021; F21S 43/19
